Primary Examiner — Paula Greene(74) *Attorney, Agent, or Firm* — Loginov & Associates; William A. Loginov(57) **CLAIM**

The ornamental design for wearable computing device, as shown and described.

DESCRIPTION

FIG. 1 is a perspective view of a wearable computing device showing multiple interior windows, according to the embodiment showing our new design;

FIG. 2 is a top plan view of the wearable computing device design, according to the embodiment;

FIG. 3 is a bottom plan view of the wearable computing device design, according to the embodiment; and,

FIG. 4 is a view of the exterior surface of the wearable computing device design, all sides being uniform.
